US00D888090S

(12) **United States Design Patent** (10) Patent No.: **US D888,090 S**
 Williams et al. (45) Date of Patent: ** Jun. 23, 2020

(54) **DISPLAY SCREEN OR A PORTION THEREOF WITH A GRAPHICAL USER INTERFACE**

(71) Applicant: **Philo, Inc.**, San Francisco, CA (US)

(72) Inventors: **Devon Ray Williams**, Berkeley, CA (US); **Andrew McCollum**, San Francisco, CA (US); **Benjamin Paul Clemens**, Berkeley, CA (US)

(73) Assignee: **PHILO, INC.**, San Francisco, CA (US)

(**) Term: **15 Years**

(21) Appl. No.: **29/625,867**

(22) Filed: **Nov. 13, 2017**

(51) LOC (12) Cl. **14-04**

(52) U.S. Cl.

USPC **D14/488**; D14/491

(58) **Field of Classification Search**

USPC D14/485-495
CPC .. H04H 60/72; H04N 5/44543; G10H 1/0008;
G06F 17/30053

(57) **CLAIM**

The ornamental design for a display screen or a portion thereof with a graphical user interface, as shown and described.

DESCRIPTION

The FIGURE is a front view of a display screen or a portion thereof with a graphical user interface, according to our new design.

The broken lines showing the display screen and the remainder of the graphical user interface form no part of the claimed design.
